TRACK BRAKE ARRANGEMENT

Sam E. Mason, San Diego, Calif., assignor to
Transit Research Corporation, a corporation of
New York

Application October 10, 1939, Serial No. 298,840

7 Claims. (Cl. 188—165)

This invention relates to magnetic brakes for rail vehicles and particularly to shoes therefor. The principal object of the invention is to provide a shoe of such construction as will reduce rail wear.

The runners or wear plates of a magnetic track brake are fastened to the shoe parallel to each other and in spaced relation thus leaving a gap between them. They contact a rail jointly and longitudinally, that is, parallel to the direction of travel with the result that the rail is worn by the runners in parallel surfaces separated by a ridge. This ridge becomes very pronounced at regular stops and on steep grades and is objectionable both as a matter of rail deterioration and because of the reduction of contact between the rail and the wheel. It is the principal object of this invention to eliminate the ridging of the rail and to accomplish this without additional cost or material reorganization of existing production parts.

More particularly, it is the object to provide runners or wear plates mounted in mutually spaced relation with the walls of the gap thus formed in parallel relation with respect to each other, but non-parallel with respect to the direction of travel, the angularity with respect to the direction of travel being proportionate to the length of the runners and the width of the gap in such manner that the entire top surface of the rail is contacted by one or the other of said runners.

Other objects and advantages will become more fully apparent as reference is had to the accompanying drawing wherein my invention is illustrated, and in which:

Fig. 1 is a side elevation of a track brake shoe with my invention incorporated therein,

Fig. 2 is a longitudinal section taken on the line 2—2 of Fig. 1, indicating its position in relation to the associated rail,

Fig. 3 is a cross section taken on the line 3—3 of Fig. 1,

Fig. 4 is a plan view, largely diagrammatic, of a pair of brake shoes strapped together.

Referring first to Fig. 3, the reference character 1 designates generally the core of an electro-magnet and the surrounding coils to which current is supplied by electric power lines 2 and 3 at the will of the operator of the vehicle to which the shoe is attached. Side members 4 correspond to the legs of a U-shaped magnet and are connected to the core 1 for energization therewith. The runners or wear members 5 are secured to side members 4 by bolts 7, the heads 7a

engage shoulders 6 on the side members 4, and the screwthreaded ends of which engage in screwthreaded holes 8 in the wear members 5.

For securing the side members 4 to the core 1, heavy bolts 9 are employed. These bolts 9 pass through the core 1 and at each end are provided with nuts 10. The bolts 9 also carry the brackets 12 for connecting the shoe to the supporting springs (not shown), which raise the shoes from the rail 13 when the coils 1 are not energized.

The description thus far has been of a single shoe, but it will be understood that each rail truck is equipped with a pair of such shoes, one between tandem wheels on opposite sides of the truck.

15 As shown in Figs. 2 and 4 each shoe is positioned at a slight angle inwardly of the axis of the rails 13 in such a manner that the displacement of one end of the shoe is equal to or greater than the width of the gap between the wear surfaces, so that the top surface of the rail must be contacted by one or the other of the runners without interruption. If desired, the angle may be great enough so that the transverse sections wiped by each runner 5 will substantially overlap. 20 Preferably the distance between the brakes at their leading edge will be as close as the gauge of the rails will permit and as great at the trailing edge as the outside to outside measurement of the ball of the rail will permit.

25 Fig. 4 shows the preferred method of positioning a pair of shoes. Complementary rods 14 are secured in any suitable manner to the inner side of each shoe, one adjacent the leading edge and one adjacent the trailing edge. Each rod 14 is in 30 two parts joined together by a connection 15 of a type to permit longitudinal adjustment thereof. The shoes may be adjusted into conventional parallel relation or they may be made to converge or diverge or they may be made to slope 35 similarly with respect to the direction of travel. The preferred adjustments are, as illustrated, wherein the leading edges converge or "toe in" or the reverse of this to diverge or "toe out".

40 What I claim is:

45 1. The combination of two magnetic brake shoes each having wear surfaces separated by a gap, and means maintaining the wear surfaces of said shoes out of parallel with respect to their direction of travel, the extent to which said shoes 50 are out of parallel being so proportioned to the length of the wear surfaces and the width of the gaps that each end of each wear surface laterally overlaps the remote end of another wear surface separated therefrom by a gap.

55 2. The combination of two magnetic brake

shoes each having substantially parallel wear surfaces separated by a gap, means connecting said shoes together, said means maintaining the wear surfaces of respective shoes in converging relation with respect to their normal direction of travel during contact with a rail, the angle of convergence being such that one end of each wear surface is laterally spaced from the plane of its other end a distance at least equal to the width of the gaps.

3. The combination of two magnetic brake shoes each having substantially parallel wear surfaces separated by a gap, means connecting said shoes together, said means maintaining the wear surfaces of said shoes in diverging relation with respect to their normal direction of travel during contact with a rail, the angle of divergence being such that one end of each wear surface is laterally spaced from the plane of its other end a distance at least equal to the width of the gaps.

4. The combination of a rail, a magnetic brake shoe having parallel wear surfaces separated by a gap, and means maintaining said wear surfaces in equally converging relation with respect to their normal direction of travel during contact with a rail, the amount of convergence from said direction of travel of the wear surfaces of each shoe being such that the forward end of each wear surface is laterally spaced from the plane of the rear end a distance equal to or greater than the width of said gap.

5. The combination of a rail, a magnetic brake shoe having parallel wear surfaces separated by a gap, and means maintaining said wear surfaces in equally diverging relation with respect to their normal direction of travel during contact with a rail, the amount of divergence from said direction of travel of the wear surfaces of each shoe being such that the rear end of each wear surface is laterally spaced from the plane of its forward end a distance equal to or greater than the width of said gap.

6. The combination of two magnetic brake shoes each having wear surfaces of less width than the rail they are adapted to contact, and means connecting said shoes together, said means being adjustable to vary the angular position of said wear surfaces with respect to their direction of travel, whereby each wear surface contacts a rail width greater than the width of the wear surface.

7. The combination of two magnetic brake shoes, rigid connections joining the respective front and rear portions of said shoes, and means incorporated in each of said connections operative to increase or to decrease the distance between the front and rear portions of said shoes whereby said shoes may be made horizontally parallel or non-parallel.
